ELECTRICAL COMMUNICATION SYSTEM

Paul Curry, New Haven, Conn.

Application November 2, 1946, Serial No. 707,348

12 Claims. (Cl. 250—6)

1

The present invention relates to systems whereby speech, music, or other intelligence may be communicated to and received at another location. Such electrical communication-systems may be either via wire or may be wireless in character.

The present application constitutes a continuation-in-part of my copending application Ser. No. 524,545, filed March 1, 1944, now abandoned.

One of the objects of the present invention is to provide a superior communication-system whereby the reception of intelligence by unauthorized persons is made exceedingly difficult if not impossible.

Another object of the present invention is to provide a superior communication-system of the character referred to which may be utilized either for wireless or wired communications.

A further object of the present invention is to provide a superior electrical communication-system of such character that a maximum number of communication channels becomes available without interference.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes;

Fig. 1 is a diagrammatic view of one form of wireless sending- or transmitting-apparatus suitable for carrying out the present invention and designed to transmit two carrier-waves both of which are frequency-modulated and amplitude-modulated;

Fig. 2 is a similar view of a wireless receiving apparatus suitable for receiving the doubly-modulated carrier-waves of the sending-apparatus of Fig. 1, or Fig. 4;

Fig. 3 is a view schematically illustrating one example of the frequency-modulation characteristics which the two doubly-modulated transmitted carrier-waves may have, together with the frequency-modulation characteristics of a wave which may be generated at the receiving-station;

Fig. 4 is a view similar to Fig. 1, but illustrating another form of sending- or transmitting-apparatus designated to transmit two carrier-waves both of which are doubly-frequency-modulated;

Fig. 5 is a schematic representation of a carrier-wave having basic-frequency-modulation;

Fig. 6 is a similar view of a signal-wave suit-

2

able for additionally modulating the carrier-wave shown in Fig. 5;

Fig. 7 is a schematic representation of the frequency-modulated carrier-wave of Fig. 5, as additionally amplitude-modulated by the signal-wave of Fig. 6; and

Fig. 8 is a schematic representation of the frequency-modulated carrier-wave of Fig. 5, as additionally frequency-modulated by the signal-wave of Fig. 6.

10 The particular electrical communicating-apparatus or -system herein chosen for purposes of illustrating one form of the present invention, is primarily designed for wireless communication, though, as will hereinafter appear, is equally suitable for use in connection with a system in which conductors connect a transmitting-station and a receiving-station.

THE APPARATUS OF FIGS. 1 AND 2

20 The apparatus illustrated includes a transmitting-antenna 10ab and a receiving-antenna 11ab. In order to afford a better understanding of the apparatus which will be more fully hereinafter described, it may be here stated that the transmitting-antenna 10ab coincidentally sends out to the receiving-antenna 11ab, two separate frequency-modulated electro-magnetic carrier-waves. Each of the said carrier-waves has both 25 its upper frequency-limit and its lower frequency-limit differing from the similar limit of the other carrier-wave, and both of the said carrier-waves being further modulated (amplitude-modulated, in the instance shown) by imposing the signal to be transmitted on both of the said carrier-waves, but in an out-of-phase relationship respectively. The two doubly-modulated carrier-waves picked up by the receiving-antenna 11ab are handled in 30 a manner as will be later described under the heading "Receiving system." The transmitting-system or -apparatus will be first described.

THE TRANSMITTING SYSTEM

For clarity of description, it may be assumed 45 that the transmitting-apparatus illustrated in Fig. 1 is transmitting two separate doubly-modulated electro-magnetic carrier-waves respectively indicated in both Figs. 1 and 2 by the arrows A and B. Where feasible, such elements as are used in conjunction with both of the waves A and B will respectively bear a reference character with the subscript "ab," while such elements as are primarily used in conjunction only with the wave A will respectively bear a reference character with a subscript "a." Similarly, such ele-

ments as are involved primarily only with the wave B will bear reference characters followed by the subscript "b."

THE APPARATUS FOR PRODUCING THE DOUBLY-MODULATED WAVE A

To provide the doubly-modulated wave A, a wave-generating unit 12a is employed which is connected through a high-pass filter 13a to an amplifying-unit 14a. The amplifying-unit 14a just referred to is, in turn, inductively coupled to a combination rectifying-and-amplifying unit 15a. The unit 15a is, in turn, inductively coupled to an amplifying-unit 16a which, in turn, is coupled through a band-pass filter 17a to an amplitude-modulator 18a. The amplitude-modulator 18a is connected to a signal-input unit designated by the reference character 19ab, and which is also used in connection with the wave B, as will later appear.

The wave-generator 12a above referred to, receives a frequency-modulating wave from a frequency-modulator 20ab which, incidentally, is also used in connection with the wave B previously referred to, all as will more fully hereinafter appear. The output of the frequency-modulator 20ab just referred to, is connected to an amplifying-unit 21ab which, like the frequency-modulator 20ab, is also used in conjunction with the wave B. The output of the amplifying-unit 21ab is connected to an amplifying-unit 22a, which latter in turn has its output connected to the wave-generator 12a before referred to.

Preferably and as shown, the input-side of the frequency-modulator 20ab above described, is connected to an amplitude-limiting unit 23ab in such manner as to impose a limit on the amplitude of the wave produced by the frequency-modulator 20ab.

The various wires interconnecting the features above described do not require detailed description, other than to note that the input of the amplitude-limiting unit 23ab is connected to the output of the amplitude-modulator 18a.

The output of the amplitude-modulator 18a above described, is connected by a coupling-transformer 24a to the transmitting-antenna 10ab.

The amplitude-limiting unit 23ab includes a primary inductance-coil 25ab which is connected through a condenser 26ab to the output of the amplitude-modulator 18a. The primary inductance-coil 25ab cooperates with two secondary inductance-coils 27ab and 28ab forming features of the unit 23ab. Each of the secondary inductance-coils 27ab and 28ab has respectively connected across it one of two variable condensers 29ab and 30ab, each of which acts in conjunction with its complementary inductance-coil to provide a resonant circuit.

The tuned circuit in which the secondary inductance-coil 27ab and the condenser 29ab are included, is resonant to a frequency widely different from the resonant-frequency of the circuit in which the coil 28ab and condenser 30ab are included. Therefore, the primary inductance-coil 25ab is so constructed as to pass the two frequencies to which the circuits of the secondary coils 27ab and 28ab are respectively responsive.

The circuit of the elements 27ab—29ab includes one of the plates of a twin diode electronic tube 31ab, while the circuit in which the elements 28ab—30ab are located is connected to the other of the plates of the said tube.

It may here be noted that the resonant circuit in which the elements 27ab—29ab are included,

develops a voltage which is opposite to the voltage developed by the energy in the resonant circuit of which the elements 28ab—30ab form a part. These opposed voltages appear alternately at the output of the amplitude-limiting unit 23ab and are applied to the grid of a gas-filled triode 32ab forming a feature of the frequency-modulator 20ab before referred to.

In addition to the gas-filled triode 32ab, the frequency-modulator 20ab also includes suitable resistors and a variable condenser as shown, to thus produce an output-wave having saw-tooth or logarithmic characteristics.

As before noted, the output of the frequency-modulator 20ab is connected to the input of the amplifying-unit 21ab. The amplifying-unit 21ab is used in conjunction with the production of both of the waves A and B before referred to, and includes a pentode electronic tube generally designated by the reference character 33ab. It is the control-grid of the tube 33ab which is connected through a suitable resistor and variable condenser to the output of the frequency-modulator 20ab. The output-lead of the amplifying-unit 21ab is electrically connected to the amplifying-unit 22a before referred to, as well as to a second amplifying-unit 22b which will be later referred to.

The amplifying-unit 22a just referred to serves now only in connection with the production of the wave A before referred to and includes a triode electronic tube generally designated by the reference character 34a. The adjuncts of the triode 34a just referred to are clearly shown in Fig. 1 and do not require detailed description other than to note that the cathode of the tube 34a constitutes the output of the amplifying-unit 22a and is connected to the input of the wave-generator 12a before referred to.

The wave-generator 12a includes a triode electronic tube generally designated by the reference character 35a, which is here utilized as a super-regenerative detector or blocking-oscillator tube in a manner well understood in the art. The adjuncts of the tube 35a are schematically represented in Fig. 1 and do not require detailed description other than to possibly mention that it is the cathode of the tube 35a which is connected to the output of the amplifying-unit 22a. The plate-circuit of the tube 35a is connected to the high-pass filter 13a before referred to, which latter, in turn, is connected to the input of the amplifying-unit 14a.

The amplifying-unit 14a includes a pentode electronic tube 36a having its control-grid circuit connected to the output of the high-pass filter 13a, as is indicated in Fig. 1. Here again, the adjuncts of the amplifying-unit 14a do not require detailed description other than to note that the plate-circuit of the tube 36a is made resonant by the inclusion of a condenser 37a and a primary inductance-coil 38a.

The primary inductance-coil 38a of the amplifying unit 14a cooperates with a secondary inductance-coil 39a constituting the input of the combined rectifying-and-amplifying unit 15a. The coil 39a just referred to, in conjunction with a condenser 40a, provides a resonant circuit connected across the diode section of a combined diode-triode electronic tube generally designated by the reference character 41a. The output of the resonant circuit which includes the elements 39a and 40a, is connected to the grid of the triode section of the tube 41a, while the load-resistor

5
62a and associated condenser 53a of the diode-section are connected to the cathode of the tube 41a through a biasing-battery 42a, which latter serves to impose a bias-voltage on the grid of the triode-section of the combination tube 41a, as is clearly shown in Fig. 1. The plate of the triode-section of the tube 41a includes a primary inductance-coil 43a.

The primary inductance-coil 43a of the unit 18a cooperates with a secondary inductance-coil 44a forming a feature of the amplifying-unit 18a. One terminal of the secondary inductance-coil 44a is connected to the control-grid of a pentode electronic tube 45a forming a feature of the amplifying-unit 18a. The adjuncts of the tube 45a are clearly illustrated in Fig. 1 of the drawings and do not require detailed description other than to note that the plate of the tube 45a is connected to the input of the band-pass filter 17a before referred to.

The output of the band-pass filter 17a is connected to a coupling-circuit which includes a coupling-condenser 46a and an inductance-coil 47a, forming, in the instance shown, features of the amplitude-modulator 18a before referred to. The circuit which includes the elements 46a and 47a, is so constituted as to pass the band-width of frequencies which is the output of the filter 17a. The circuit of the elements 46a and 47a is connected to the control-grid of a pentode electronic tube 48a, also included as a feature of the amplitude-modulator 18a.

The features of the amplitude-modulator 18a do not require further detailed description other than to note that the plate of the tube 48a is connected to the primary of the antenna-coupling transformer 24a before referred to. Further note may be had of the fact that the suppressor-grid of the tube 48a is connected to one section of the secondary coil of the transformer of the signal-input unit 19ab before referred to.

THE APPARATUS FOR PRODUCING THE DOUBLY-MODULATED WAVE B

To provide the doubly-modulated wave B (a companion of the Wave A), a wave-generating unit 12b is employed, as are also elements respectively designated 13b, 14b, 15b, 16b, 17b, 18b, 22b and 24b and respectively corresponding to the units 12a to 18a inclusive and 22a and 24a.

The elements previously described in connection with the various instrumentalities 12a to 18a inclusive and 22a and 24a, are duplicated in the similar elements which are designated by the subscript "b" and bear like reference characters save that they bear the subscript "b" instead of the subscript "a."

From the foregoing it will appear that the output of the amplifying-unit 21ab flows to both the amplifying-units 22a and 22b. The plate of the tube 48b of the amplitude-modulator 18b is connected to the primary on the antenna-coupling transformer 24b. It should also be noted that the suppressor-grid of the tube 48b is connected to the section of the secondary of the signal-input unit 19ab opposite to that to which the suppressor-grid of the tube 48a is connected. Thus, the voltage applied to the suppressor-grid of the tube 48a will be in phase-opposition to the voltage applied to the suppressor-grid of the tube 48b.

In conjunction with the transmitting-apparatus above described, three batteries or other suitable sources of electrical energy 49ab, 50ab

and 51ab are employed. In the particular instance shown, the battery 49ab serves to supply the heaters of the various electronic tubes employed in the transmitting system, while the battery 50ab is suitably connected to such of the various electronic tubes as include a screen-grid to impress a suitable intermediate voltage on such screen-grids. The battery 51ab in conjunction with the battery 50ab, is connected to the respective plates of the various electronic tubes of the transmitting-system with the exception of the twin diode-plates of the tubes 31, 41a and 41b.

THE EVOLUTION OF A TYPICAL WAVE A

For purposes of clarity of description, let it be assumed that the wave A with respect to its frequency-modulated characteristics, has a band-width having a lower frequency-limit of 900 kilocycles and an upper frequency-limit of 1800 kilocycles.

Under the circumstances above outlined, the wave-generator 12a, which is a self-blocking super-regenerative detector or oscillator will be constructed and arranged to produce a fundamental-wave having a fundamental-frequency of 50 kilocycles, together with the harmonic-frequencies thereof, which latter have pronounced values. This fundamental-frequency will, however, be frequency-modulated by the frequency-modulator 20ab so as to result in recurrent groups of waves each corresponding to the others both in pattern and in time-interval and all of which groups occur between an upper frequency-limit of 50 kilocycles and a lower frequency-limit of 35.25 kilocycles. The resultant frequencies between the limits just referred to, represent the rates of quenching or suppression of the wave-generator 12a. The harmonic-frequencies of the aforesaid fundamental-frequency will also be frequency-modulated by the frequency-modulator 20ab.

It may here be noted that the output of the frequency-modulator 20ab, before its application to the wave-generator 12a, is amplified by the amplifying-unit 21ab and the amplifying-unit 22a.

Under the circumstances above described, the frequency-modulator 20ab will have an output-frequency of 10 kilocycles, in order to jointly with the wave-generator 12a, contribute to the frequency-modulated characteristics of the wave A. Furthermore, the output of the frequency-modulator 20ab is characterized by a logarithmic or sawtooth wave-form (rather than a sinusoidal wave-form) having the time of its rise corresponding to the time of its decline. While the output-wave of the frequency-modulator 20ab is logarithmic in character as just noted, nevertheless, such logarithmic wave-form is kept as near to linear rise and decline respectively, as is feasible. Such linear characteristics enable the present system to operate with maximum facility, though they are not essential.

At this point, it is well to here note the function of the amplitude-limiting unit 23ab. This unit 23ab serves to limit the amplitude of the output of the frequency-modulator 20ab, in order to hold the frequency-limits of the wave A (as well as the wave B) at predetermined values. Thus, under the conditions here being described, the resonant network comprising the elements 21ab and 29ab will preferably be broadly tuned to a band between about 900 kc. and 1000 kc., while the network comprising the elements 28ab and

20ab will be broadly tuned to a band between about 1800 kc. and 2000 kc.

Returning now to the output of the wave-generator **12a** which, as before described, comprises recurrent groups of fundamental-waves and recurrent groups of the harmonic-frequencies thereof, it is to be noted that such groups of waves and the harmonic-frequencies thereof (all of which have been frequency-modulated) are applied to the input of the high-pass filter **13a**.

Under the particular circumstances now being considered, the characteristics of the high-pass filter **13a** will be such as to cause the maximum attenuation of all frequencies below about 7,650 kilocycles in value (inclusive of the aforesaid group of fundamental-waves), while causing the minimum attenuation of all of the frequencies at and above about 7,650 kilocycles. The net result will be that at the output of the high-pass filter **13a**, the frequencies at and above about 7,650 kilocycles in value will appear with sufficient value to be employed in the subsequent steps of the system, whereas, the frequencies below about 7,650 kilocycles will have negligible values and will not affect the subsequent steps of the system.

As before noted, the amplifying-unit **14a** has a resonant network which includes the elements **37a** and **38a** which, in conjunction with the resonant circuit (including the elements **39a** and **40a**) of the unit **15a**, will freely pass only the selected frequency which, in this instance, will be a relatively narrow band centered at about 7,650 kilocycles. The frequency-band last referred to will, of course, have been amplified in the unit **14a**. As is well known in the art, frequencies other than the selected frequency of about 7,650 kilocycles, will pass from the unit **14a** to the unit **15a**, but in such negligible amplitude as not to affect the following stages of the system.

With the particular relationship being described, the group of frequency-modulated harmonic-frequencies extending between and including the 153d to 217th will successively appear in the resonant network comprising the elements **37a** and **38a** of the unit **14a** and the elements **39a** and **40a** of the unit **15a**. The said group of harmonic frequencies will, however, only pass through the said network at the instant that they respectively successively come into resonance therewith. As each of the aforesaid frequency-modulated harmonic-frequencies (sixty-four in number) successively appears in the resonant network just referred to, each will at some point in the cycle of its frequency-change, come into resonance (about 7,650 kilocycles) with the aforesaid resonant network, and will, while in substantial resonance, cause an increment of energy to appear in the said resonant network. Owing to their frequency-modulated character, the time-intervals between the respective maximum-values of the said increments of energy, will vary. This variation in time-intervals results from the fact that the different harmonic-frequencies of the aforesaid fundamental-wave, progressively vary arithmetically in time-interval. Thus, the time-interval between the 153d and the 154th harmonics may, for convenience of illustration, be considered to be equal to $1/53$, in which case the relative time-interval between the 154th and the 155th harmonics will be smaller and equal to $1/154$ and so on to the 216th and 217th harmonics which will have a still smaller relative time-interval of $1/216$. It is this arithmetical progression or relationship which determines the ultimate frequency-modulation characteristics of the wave A.

The radio-frequency components of each of the increments of energy just above referred to, will vary in amplitude and the said increments will occur in groups of sixty-four which groups provide what is commonly known in the art as a "wave-envelope."

The radio-frequency waves representing each of the aforesaid increments of energy are rectified by the diode-section of the tube **41a**, with the result that half of each of the said waves and half of the envelope thereof, are eliminated. The remaining halves of the said waves are so filtered by the load-resistor **52a** and its complemental condenser **53a**, that there appears (amplified) in the output of the triode section of the tube **41a**, a new frequency-modulated fundamental-wave having frequency-limits respectively at 900 kilocycles and 1800 kilocycles, together with a series of harmonic-waves representing harmonics of all the waves occurring between the said limits of 900 kilocycles and 1800 kilocycles inclusive.

It may be here shown, by example, through one cycle of operation, how the output of the unit **20ab**, in conjunction with the operation of blocking oscillator **12a** and the tuned network comprising the elements **37a**, **38a**, **39a** and **40a** which is tuned to a relatively narrow band centered on 7650 kilocycles, as well as the rectifying network in which the elements **39a** and **40a** are included, contribute to the creation of the new frequency-modulated wave A appearing across the diode-load-resistor **52a** and its complemental condenser **53a**.

It may be assumed, for purposes of illustration, that at time t_0 , the amplitude of the output of unit **20ab** as represented by the bias developed through the cathode resistor paralleling tube **34a** of amplifying unit **22a** and tube **35a** of blocking oscillator **12a** is $E_c + 0$, and the output of oscillator **12a** is a function having a fundamental frequency of 35.2535 kilocycles.

It may be further assumed that the frequency output of unit **20ab** is, as shown above, 10.0 kilocycles per second.

A further assumption, for purposes of illustration, is that the rising function of the output of the unit **20ab**, which equals X, and the declining function which equals $1 - X = Y$ represent straight lines. This assumption is permissible since in practical cases the logarithmic rise and decline of a saw-tooth wave can be made to approach linearity sufficiently to support the illustration.

A still further valid assumption is that the frequency variation of the output of oscillator **12a** is linear with the rise and decline of the function of the unit **20ab** output, since the actual logarithmic variation of the frequency of the **12a** oscillator output, with the variation of bias voltage across the tube **35a** cathode resistor can be made to approach linearity sufficiently to support the illustration.

The fundamental frequency of 35.2535 kilocycles, at the output of oscillator **12a**, has a large number of higher order harmonic frequencies harmonically spaced in frequency, so that the second harmonic has a frequency of 70.507 kilocycles, the third harmonic has a frequency of 105.7605 kilocycles, etc. It can be seen therefore, that the 217th harmonic has a frequency of, substantially, 7,650 kilocycles, and is, therefore, in resonance with the tuned network comprising the elements **37a**, **38a**, **39a** and **40a**. In consequence, the voltage developed across the element **52a**, which, together with its complemental condenser **53a**, forms the load network of the diode

rectifier of the tube 41a, is at maximum. At time t_1 , the amplitude of the output of unit 28ab is $E_0 + .025$ volt, and the output of blocking oscillator 12a has changed, as a result of the change in bias voltage, to 35.3302 kilocycles. The frequency of the 217th harmonic is now 7,666.6534 kilocycles, and is therefore substantially out of resonance with the tuned network comprising elements 37a, 38a, 39a and 40a. And, since the 216th harmonic has a frequency of 7,631.3232 kilocycles it, too, is substantially out of resonance with the tuned network comprising elements 37a, 38a, 39a and 40a. As a result, the voltage developed across the diode load resistor 52a is at a minimum.

At time t_2 , the amplitude of the output of unit 28ab is such as to develop a bias of $E_0 + .05$ volt across the tube 38a cathode resistor, and the output of blocking oscillator 12a is now 35.4166 kilocycles, as a result of this further change in bias. The 217th harmonic is now further out of resonance while the 216th harmonic has come into substantial resonance with the tuned network comprising the elements 37a, 38a, 39a and 40a, and the voltage developed across the diode-load-resistor 52a is again at maximum.

It can be seen from the description above, that from time t_0 to time t_2 the voltage developed across the diode-load-resistor 52a has described a function which possesses a decline for the period from time t_0 to time t_1 , and a rise from time t_1 to time t_2 . And the decline, together with the rise, constitute a wave function which can be mathematically resolved into a fundamental sine wave, plus a large number of sine wave harmonics of the said fundamental sine wave.

It may be convenient to further inspect the successive values involved in this example by means of the following table in which the first column heading "Time" indicates the progress of time from t_0 to t_n , while the function of the output of unit 28ab is rising from zero to maximum, and from t_n to t_{n+1} , while the function is declining from maximum to zero again, this representing one cycle in the operation of the unit 28ab.

Table

Time	Effect on 25s Bias by 28ab Output (Volts)	Freq. Out-put of Osc. 12a (Kc.)	Harm. at Reson. (7,650 Kc.)	Harms. Near Reson. (7,650 Kc.)	Freq. of Harm. at Reson. (Kc.)	Freq. of Harms. Near Reson. (Kc.)	Voltage Across Load Resistor 52a
t_0	$E_0 + 0$	35.2535	217th		7,650		Maximum.
t_1	$E_0 + .025$	35.3302		217-216		7,666-7,631	Minimum.
t_2	$E_0 + .05$	35.4166	216th		7,650		Maximum.
t_3	$E_0 + .075$	35.4988		216-215		7,667-7,632	Minimum.
t_4	$E_0 + .10$	35.5814	215th		7,650		Maximum.
t_5	$E_0 + .145$	49.3548	155th		7,650		Do.
t_6	$E_0 + .415$	49.5145		155-154		7,625-7,674	Minimum.
t_7	$E_0 + .4675$	49.6753	154th		7,650		Maximum.
t_8	$E_0 + .4735$	49.8371		154-153		7,625-7,674	Minimum.
t_9	$E_0 + .48$	50.00	153d		7,650		Maximum.
t_{10}	$E_0 + .4735$	49.8371		153-154		7,674-7,625	Minimum.
t_{11}	$E_0 + .4675$	49.6753	154th		7,650		Maximum.
t_{12}	$E_0 + .025$	35.3302		216-217		7,631-7,666	Minimum.
t_{13}	$E_0 + 0$	35.2535	217th		7,650		Maximum.

By examining the above table it can be seen that from time t_0 to time t_2 , the voltage on the load resistor 52a varies from maximum when the 217th harmonic is in resonance with the tuned network comprising elements 37a, 38a, 39a and 40a, through minimum when the harmonics nearest the resonance frequency of the tuned network are out of resonance, and back to maximum when the 216th harmonic is in resonance with the tuned network. This represents one complete cycle of a wave function having a period equal to the time interval from t_0 to t_2 .

68 wave-functions developed across the diode-load-resistor 52a is downward, until the interval $t_{n-4}-t_{n-2}$.

Returning to the table it can be seen that the frequency differentiation of the oscillator 12a output for the interval $t_{n-4}-t_{n-2}$, is .3205 kilocycle and since the frequency variation during $\frac{1}{20,000}$ second is 14.7465 kilocycles the time interval represented by $t_{n-4}-t_{n-2}$ is $.3205/14.7465 \times .00005$ equals .00000108665 second. The wave-function occurring during the interval $t_{n-4}-t_{n-2}$

would, if it were recurrent, have a frequency of 920.2 kilocycles.

In a similar manner, the frequency differentiation of the oscillator 12a output for the interval $t_{n-2}-t_n$, shown in the table, is .3247 kilocycle and the time interval represented, therefore, is .3247/14.7465 $\times$ .00005 equals .0000011005 second.

This wave-function would, if it were recurrent, have a frequency of 908.6 kilocycles, and this is substantially near the lower limit frequency (900 10 kc.) of the wave A as shown in the disclosure.

The interval t_n-t_{n+2} , shown in the table is the same as the interval $t_{n-2}-t_n$, for, while the period from t_0 to t_n represents the rising function of the output of the unit 20ab, the period from t_n to t_{n+2} represents its declining function. The frequencies occurring during the period t_n-t_{n+2} are the same as those occurring during the period t_0-t_n , but occur in reverse order. Thus, the frequency variation from time t_0 to time t_n is from 1,808.3 kilocycles to 908.6 kilocycles, and the frequency variation from time t_n to time t_{n+2} is 908.6 kilocycles to 1,808.3 kilocycles.

This fundamental-wave, together with its harmonic-waves, will appear in the primary inductance-coil 43a of the unit 15a and will be transferred to the secondary inductance-coil 44a of the amplifying-unit 16a. The unit 16a merely serves to amplify these waves and supply them to the input of the band-pass filter 17a.

The band-pass filter 17a is designed and adapted to so attenuate the harmonic-waves supplied to it as to render them negligible in value at the output of the said filter, whereas, the fundamental-wave having frequency-limits between 900 kilocycles and 1800 kilocycles inclusive, will be passed with minimum attenuation and is impressed upon the control-grid of the pentode-tube 48a of the amplitude-modulator 18a.

The fundamental-wave (carrier-wave) last above referred to may, for the sake of clarity of illustration, be assumed to have the basic characteristics schematically illustrated in Fig. 5, though it is impossible, as a practical matter, to illustrate the carrier-wave having the actual frequency-limits referred to.

The wave above referred to, which is applied to the control-grid of the tube 48a of the amplitude-modulator 18a, results in the appearance in the plate-circuit of the said tube of a frequency-modulated wave which, however, is also amplitude-modulated by the signal applied to the suppresser-grid of the tube 48a from its half of the secondary inductance-coil of the signal-input unit 19ab. In this connection, it may be explained that the voice or other intelligence which it is desired to transmit, is applied to the said unit 19ab, and this resultant signal-wave may be assumed to have the form shown in Fig. 6, though it is not practical to show a normal actual signal-frequency.

The wave appearing in the plate-circuit of the tube 48a of the amplitude-modulator 18a as above described, is the now-doubly-modulated wave A before referred to, and may, for purposes of understanding the fundamentals here involved, be assumed to be basically like the doubly-modulated wave shown in Fig. 7. This wave A is applied to the primary inductance-coil of the coupling-transformer 24a and is transferred thereby to the secondary inductance-coil of the said transformer and by the latter is applied to the transmitting-antenna 10ab or, if desired, to a wired-circuit.

The wave A as above described, is doubly modu-

lated in the sense that it is both frequency-modulated and amplitude-modulated, though, as will hereinafter appear in connection with the description of Fig. 4, the wave A may be doubly frequency-modulated.

THE EVOLUTION OF A TYPICAL WAVE B

A wave B suitable for use in conjunction with the wave A before described, may have, with respect to its frequency-modulated characteristics, a band-width having a lower frequency-limit of 1,000 kilocycles and an upper frequency-limit of 2,000 kilocycles.

Under the circumstances above outlined, the wave-generator 12b (which is a self-blocking super-regenerative detector or oscillator) will be constructed and arranged to produce a fundamental-wave having a fundamental-frequency of 50 kilocycles, together with the harmonic-frequencies thereof, which latter have pronounced values. This fundamental-frequency will, however, be frequency-modulated by the frequency-modulator 20ab, so as to result in recurrent groups of waves, each corresponding to the others in both pattern and time-interval, and all of which groups occur between an upper frequency-limit of 50 kilocycles and a lower frequency-limit of 35.42 kilocycles. The resultant frequencies between the limits just referred to, represents the rate of quenching or suppression of the wave-generator 12b. The harmonic-frequencies of the aforesaid fundamental-frequency will also be frequency-modulated by the frequency-modulator 20ab.

It is well to here note that the output of the frequency-modulator 20ab, before its application to the wave-generator 12b, is amplified by the amplifying-unit 21ab and the amplifying-unit 22b.

Under the circumstances above described, the frequency-modulator 20ab will, as before noted, have an output-frequency of 10 kilocycles, in order to jointly with the wave-generator 12b, contribute to the frequency-modulated characteristics of the wave B. The output of the frequency-modulator 20ab is, as before pointed out, characterized by a logarithmic or saw-tooth wave-form having the time of its rise corresponding to the time of its decline. While the output-wave of the frequency-modulator 20ab is logarithmic in character, as just noted, nevertheless such logarithmic wave-form is kept as near to linear rise and decline respectively, as is feasible.

The amplitude-limiting unit 23ab performs in connection with the evolution of the wave B in the same manner as that described in connection with the evolution of the wave A.

Returning now to the output of the wave-generator 12b, attention is again called to the fact that the said output comprises recurrent groups of fundamental-waves and recurrent groups of the harmonic-frequencies thereof. It is to be noted that such groups of waves and the harmonic-frequencies thereof (all of which have been frequency-modulated) are applied to the input of the high-pass filter 13b.

Under the particular circumstances now being considered, the characteristics of the high-pass filter 13b will be such as to cause the maximum attenuation of all frequencies below about 8,500 kilocycles in value (inclusive of the aforesaid groups of fundamental-waves), while causing the minimum attenuation of all of the frequencies at and above about 8500 kilocycles. The net result will be that at the output of the high-pass

filter 13b, the frequencies at and above about 8,500 kilocycles in value will appear with sufficient value to be employed in the subsequent steps of the system, whereas, the frequencies below about 8,500 kilocycles will have negligible values and will not affect the subsequent steps of the system.

As before noted, the amplifying-unit 14b has a resonant network which includes the elements 37b and 38b which, in conjunction with the resonant network (including the elements 39b and 40b) of the unit 15b, will freely pass only the selected-frequency which, in this instance, will be a relatively-narrow band centered at about 8,500 kilocycles. The frequency-band last referred to will, of course, have been amplified in the unit 14b. As is well known in the art and as before noted, frequencies other than the selected-frequency of about 8,500 kilocycles will pass from the unit 14b to the unit 15b, but in such negligible amplitude as not to affect the following stages of the system.

With the particular relationship now being described, the group of frequency-modulated harmonic-frequencies extending between and including the 170th to the 240th will successively appear in the resonant network comprising the elements 37b and 38b of the unit 14b, and the elements 39b and 40b of the unit 15b. As each of the aforesaid frequency-modulated harmonic-frequencies (seventy in number) successively appears in the resonant network just referred to, each will at some point in the cycle of its frequency-change come into resonance (about 8,500 kilocycles) with the aforesaid resonant network, and will, while in substantial resonance, cause an increment of energy to appear in the said resonant network. Owing to their frequency-modulated character, the time-intervals between the respective maximum values of the said increments of energy will vary. This variation in time-intervals results from the fact that the different harmonic-frequencies of the aforesaid fundamental-wave, progressively vary arithmetically in time-interval. Thus, the time-interval between the 170th and the 171st harmonics may for convenience of illustration, be considered to be equal to $\frac{1}{170}$, in which case the relative time-interval between the 171st and the 172d harmonics will be smaller and equal to $\frac{1}{171}$, and so on to the 239th and 240th harmonics, which will have a still smaller relative time-interval of $\frac{1}{239}$. It is this arithmetical progression or relationship which determines the ultimate frequency-modulation characteristics of the wave B.

The radio-frequency components of each of the increments of energy just above referred to will vary in amplitude and the said increments will occur in groups of seventy, which groups provide what is commonly known in the art as a "wave-envelope."

The radio frequency-waves representing each of the aforesaid increments of energy are rectified in the diode-section of the tube 41b, with the result that half of each of the said waves and half of the envelope thereof are eliminated. The remaining halves of the said waves are so filtered by the load-resistor 52b and its complementary condenser 53b that there appears in amplified form in the output of the triode-section of the tube 41b, a new frequency-modulated fundamental-wave having frequency-limits respectively at 1,000 kilocycles and 2,000 kilocycles, together with a series of harmonic-waves representing harmonics of all of the waves occurring between

the said limits of 1,000 kilocycles and 2,000 kilocycles inclusive.

It may be here shown, by example, through one cycle of operation, how the output of the unit 20ab, in conjunction with the operation of blocking oscillator 12b and the tuned network comprising the elements 37b, 38b, 39b and 40b which is tuned to a relatively narrow band centered on 8,500 kilocycles, as well as the rectifying network in which the elements 39b and 40b are included, contribute to the creation of the new frequency-modulated wave B appearing across the diode-load-resistor 52b and its complementary condenser 53b.

15 It may be assumed, for purposes of illustration, that at time t_0 , the amplitude of the output of unit 20ab as represented by the bias developed through the cathode resistor paralleling tubes 34b of amplifying unit 22b and tube 35b of blocking oscillator 12b is $E_c + 0$, and the output of oscillator 12b is a function having a fundamental frequency of 35.4166 kilocycles.

16 It may be further assumed that the frequency output of unit 20ab is, as shown above, 10.0 kilocycles per second.

17 A further assumption, for purposes of illustration, is that the rising function of the output of the unit 20ab, which equals X , and the declining function which equals $1-X=X$ represent straight lines. This assumption is permissible since in practical cases the logarithmic rise and decline of a saw-tooth wave can be made to approach linearity sufficiently to support the illustration.

18 A still further valid assumption is that the frequency variation of the output of oscillator 12b is linear with the rise and decline of the function of the unit 20ab output, since the actual logarithmic variation of the frequency of the 12b oscillator output, with the variation of bias voltage across the tube 35b cathode resistor can be made to approach linearity sufficiently to support the illustration.

19 The fundamental frequency of 35.4166 kilocycles, at the output of oscillator 12b, has a large number of higher order harmonic frequencies harmonically spaced in frequency, so that the second harmonic has a frequency of 70.8332 kilocycles, the third harmonic has a frequency of 106.248 kilocycles, etc. It can be seen therefore, that the 240th harmonic has a frequency of, substantially, 8500 kilocycles, and is, therefore, in resonance with the tuned network comprising the elements 37b, 38b, 39b and 40b. In consequence, the voltage developed across the element 52b, which, together with its complementary condenser 53b, forms the load network of the diode rectifier of the tube 41b, is at maximum.

20 At time t_1 , the amplitude of the output of unit 20ab is $E_c + .03$ volt, and the output of blocking oscillator 12b has changed, as a result of the change in bias voltage, to 35.4906 kilocycles. The frequency of the 240th harmonic is now 8,517.744 kilocycles, and is therefore substantially out of resonance with the tuned network comprising elements 37b, 38b, 39b and 40b. And, since the 239th harmonic has a frequency of 8,482.253 kilocycles it, too, is substantially out of resonance with the tuned network comprising elements 37b, 38b, 39b and 40b. As a result the voltage developed across the diode-load-resistor 52b is at a minimum.

21 At time t_2 , the amplitude of the output of unit 20ab is such as to develop a bias of $E_c + .055$ volt across the tube 35b cathode resistor, and the out-

15

put of blocking oscillator 12b is now 35.5648 kilocycles, as a result of this further change in bias. The 240th harmonic is now further out of resonance while the 239th harmonic has come into substantial resonance with the tuned network comprising the elements 37b, 38b, 39b and 40b, and the voltage developed across the diode-load-resistor 52b is again at maximum.

It can be seen from the description above, that from time t_0 to time t_2 the voltage developed across the diode-load-resistor 52b has described a function which possesses a decline for the period from time t_0 to time t_1 , and a rise from time t_1 to time t_2 . And the decline, together with the rise, constitute a wave function which can be mathematically resolved into a fundamental sine wave, plus a large number of sine-wave harmonics of the said fundamental sine wave.

It may be convenient to further inspect the successive values involved in this example by means of the following table in which the first column heading "Time" indicates the progress of time from t_0 to t_n , while the function of the output of unit 20ab is rising from zero to maximum, and from t_n to t_{n+n} , while the function is declining from maximum to zero again, this representing one cycle in the operation of the unit 20ab.

Table

Time	Effect on 35b Bias by 20ab Output (Volts)	Freq. Output of Osc. 12b (Kc.)	Harm. at Reson. (8500 Kc.)	Harms. Near Reson. (8500 Kc.)	Freq. of Harm. at Reson. (Kc.)	Freq. of Harms. Near Reson. (Kc.)	Voltage Across Load Resistor 52b
t_0	$E_0 + 0$	35.4166	240th		8,500		Maximum.
t_1	$E_0 + 0.025$	35.4906		240-239	8,500	8,517-8,482	Minimum.
t_2	$E_0 + 0.05$	35.5648	239th		8,500		Maximum.
t_3	$E_0 + 0.075$	35.6394		239-238	8,500	8,516-8,482	Minimum.
t_4	$E_0 + 0.100$	35.7142	238th		8,500		Maximum.
t_{n-4}	$E_0 + 4.55$	49.4186	172d		8,500		Do.
t_{n-3}	$E_0 + 4.61$	49.5626		172-171	8,500	8,524-8,475	Minimum.
t_{n-2}	$E_0 + 4.67$	49.7076	171st		8,500		Maximum.
t_{n-1}	$E_0 + 4.73$	49.8535		171-170	8,500	8,524-8,475	Minimum.
t_n	$E_0 + 4.80$	50.000	170th		8,500		Maximum.
t_{n+1}	$E_0 + 4.73$	49.8535		170-171	8,500	8,475-8,524	Minimum.
t_{n+2}	$E_0 + 4.67$	49.7076	171st		8,500		Maximum.
t_{n+3}	$E_0 + 0.25$	35.4906		239-240	8,500	8,482-8,517	Minimum.
t_{n+4}	$E_0 + 0.00$	35.4166	240th		8,500		Maximum.

By examining the above table it can be seen that from time t_0 to time t_2 , the voltage on the load resistor 52b varies from maximum when the 240th harmonic is in resonance with the tuned network comprising elements 37b, 38b, 39b and 40b, through minimum when the harmonics nearest the resonance frequency of the tuned network are out of resonance, and back to maximum when the 239th harmonic is in resonance with the tuned network. This represents one complete cycle of a wave function having a period equal to the time interval from t_0 to t_2 .

Since, as has been noted, the frequency of the output of unit 20ab is 10.0 kilocycles per second, and the time of the rising function of the 20ab output represents one-half cycle of operation, the time from t_0 to t_n is $1/20000$ second.

And, since the output of oscillator 12b is 35.4166 kilocycles at time t_0 , and 50.0 kilocycles at time t_n , the variation in frequency in $1/20000$ second is 14.5834 kilocycles.

The variation in frequency of the oscillator 12b output from time t_0 to time t_2 is 35.5648 minus 35.4166 equals .1482 kilocycle and, since the frequency variation during $1/20000$ second is 14.5834 kilocycles the time interval represented by t_0 to t_2 is $.1482/14.5834 \times 0.00005$ equals $.00000050811$ second.

It can be seen, therefore, that if the function of the wave developed by the voltage across the

diode-load-resistor 52b during the time t_0 to t_2 were recurrent, the frequency of that function would be 1,968 kilocycles. This frequency is substantially near one frequency limit (2000 kc.) of the wave B, as shown in this disclosure.

To determine the frequency of the voltage wave-function developed across the load-resistor 52b, during the time interval t_2 to t_4 we have a frequency differentiation in the oscillator 12b output of .1494 kilocycle, and, since the frequency variation during $1/20000$ second is 14.5834 kilocycles the time interval represented by t_2 to t_4 is,

$$.1494/14.5834 \times 0.00005$$

equals .0000005122 second.

It is seen, therefore, that if the wave-function developed by the voltage across the diode-load-resistor 52b during the time interval t_2 to t_4 were recurrent, the frequency of the wave-function would be 1,952 kilocycles. The frequency of that wave-function during the interval t_2 to t_4 is therefore 16 kilocycles lower than the wave-function during the previous interval t_0 to t_2 .

It may not be necessary to show, individually, the 70 successive voltage wave-functions appearing across the diode-load-resistor 52b during the successive time intervals t_4 to t_6 , t_6 to t_8 , etc.,

up to t_{n-4} to t_{n-2} , since it is apparent that in the interval t_4 to t_{n-4} , the curve of frequency variation of the wave-functions developed across the diode-load-resistor 52b is downward, until the interval t_{n-4} to t_{n-2} .

Returning to the table it can be seen that the frequency differentiation of the oscillator 12b output for the interval t_{n-4} to t_{n-2} , is .289 kilocycle and since the frequency variation during $1/20000$ second is 14.5834 kilocycles the time interval represented by t_{n-4} to t_{n-2} is $.289/14.5834 \times 0.00005$ equals $.000009905$ second. The wave-function occurring during the interval t_{n-4} to t_{n-2} would, if it were recurrent, have a frequency of 1,009 kilo-

cycles.

In a similar manner, the frequency differentiation of the oscillator 12b output for the interval t_{n-2} to t_n , shown in the table, is .2924 kilocycle and the time interval represented, therefore, is $.2924/14.5834 \times 0.00005$ equals $.0000010025$ second.

This wave-function would, if it were recurrent, have a frequency of 997.5 kilocycles, and this is substantially near the lower limit frequency (1000) of the wave B as shown in the disclosure.

The interval t_{n-2} to t_{n+2} , shown in the table is the same as the interval t_{n-2} to t_n for, while the period from t_0 to t_n represents the rising function of the output of the unit 20ab, the period from t_n to t_{n+2} represents its declining function. The frequencies occurring during the period t_n to t_{n+2} are

the same as those occurring during the period to t_n , but occur in reverse order. Thus, the frequency variation from time t_0 to time t_n is from 1968 kilocycles to 997.5 kilocycles, and the frequency variation from time t_n to time t_{n+1} is from 997.5 kilocycles to 1968 kilocycles.

This fundamental-wave, together with its harmonic-wave, will appear in the primary inductance-coil 43b of the unit 15b and will be transferred to the secondary inductance-coil 44b of the amplifying-unit 16b. The unit 16b merely serves to amplify these waves and supply them to the input of the band-pass filter 17b.

The band-pass filter 17b in this particular instance will be designed and adapted to so attenuate the harmonic-waves supplied to it as to render them negligible in value at the output of the said filter, whereas, the fundamental-wave having frequency-limits between 1,000 kilocycles and 2,000 kilocycles inclusive, will be passed with minimum attenuation and is impressed upon the control-grid of the pentode-tube 48b of the amplitude-modulator 18b.

The wave above referred to, which is applied to the control-grid of the tube 48b of the amplitude-modulator 18b results in the appearance in the plate-circuit of the said tube of a frequency-modulated wave which, however, is also amplitude-modulated by the signal applied to the suppresser-grid of the tube 48b from its half of the secondary induction-coil of the signal-input unit 19ab. As before explained, the voice or other intelligence which it is desired to transmit is applied to the said unit 19ab.

The wave appearing in the plate-circuit of the tube 48b of the amplitude-modulator 18b as above described, is the now-doubly-modulated wave B before referred to. This wave B is applied to the primary inductance-coil of the coupling-transformer 24b and is transferred thereby to the secondary inductance-coil of the said transformer and by the latter is applied to the transmitting-antenna 10ab or, if desired, to a wired-circuit.

The wave B above described, is doubly modulated in the sense that it is both frequency-modulated and amplitude-modulated though, as will hereinafter appear in connection with the description of Fig. 4, the wave B may be doubly frequency-modulated.

The intelligence applied to the suppresser-grid of the tube 48b will be in phase-opposition with respect to the intelligence applied to the suppresser-grid of the tube 48a, since the respective suppresser-grids receive their energy from opposite halves of the secondary inductance-coil of the signal-input unit 19ab.

THE RELATIONSHIPS OF THE WAVES A AND B

Preferably and as before noted, the respective amplitude-modulations of the waves A and B are in phase-opposition (180° apart), but in the broader aspects of the present problem direct phase-opposition is not required, though some appreciable degree of phase-differentiation should be present to make available the maximum advantages of the present system.

The primary object of the phase-differentiation between the amplitude-modulation characteristics of the wave A and B as above described, is to so distort the intelligence being transmitted as to render its reception by unauthorized persons extremely difficult, and even if the waves were successfully picked up by unauthorized persons, the intelligence carried

thereby will be difficult to extract in intelligible form.

No feasible mode is known of clearly and proportionally illustrating a composite of both the frequency-modulation characteristics and the amplitude-modulation characteristics of the respective waves A and B above referred to, but it is believed that the foregoing explanations with respect to the amplitude-modulation characteristics will be adequate. With respect to the relative frequency-modulation characteristics of the waves A and B, reference may be had to Fig. 3 of the accompanying drawings.

In Fig. 3, three waves are illustrated but the wave C may for the present be ignored, inasmuch as it is concerned with the receiving system.

In brief, it will be noted that in Fig. 3 the relationships of the waves A and B are such that each thereof has both its upper frequency-limit and its lower frequency-limit differing from the similar limits of the other of the said waves. In other words, with respect to the frequency-modulation characteristics of the waves A and B, the respective lower frequency-limits thereof do not coincide nor do the respective upper frequency-limits thereof coincide. This is the preferred relationship of the waves, though the respective upper frequency-limits of the said waves may coincide, or the respective lower frequency-limits of the said waves may coincide, but in each such instance, the relationship must be such that at least at one of the said limits, the said waves do not coincide.

THE RECEIVING SYSTEM

As is shown in Fig. 2, the receiving system includes the receiving-antenna 11ab before referred to, which antenna receives both of the doubly-modulated waves A and B described in connection with the transmitting system.

In the receiving system there is generated for purposes as will hereinafter appear, a third wave which may be designated by the reference character C, which in this particular instance has only frequency-modulated characteristics.

THE APPARATUS FOR PRODUCING THE WAVE C

To provide the singly-modulated (frequency-modulated) wave C, a wave-generating unit 54c is employed which is connected through a high-pass filter 55c to an amplifying-unit 56c. The amplifying-unit 56c just referred to is, in turn, inductively coupled to a combination rectifying-and-amplifying unit 57c. The output of the unit 57c is coupled through a band-pass filter 58c to the input of an inductive-coupling unit 59c, one of the outputs of which latter is coupled to one of the inputs of a beat-frequency-detecting or heterodyne-detecting unit 60bc. The other output of the said inductive-coupling unit 59c is connected to a beat-frequency-detecting or heterodyne-detecting unit 61ac.

The beat-frequency-detecting or heterodyne-detecting unit 60bc above referred to, is inductively coupled to an amplifying-unit 62. In turn, the output of the amplifying-unit 62 is inductively coupled to a combined rectifying-and-amplifying unit 63.

The output of the combined rectifying-and-amplifying unit 63 is connected to the primary of an audio-frequency transformer 64 having its output, in turn, connected to the input of an audio-frequency amplifier 65. The output of the amplifier 65 is, in turn, connected to the primary of an audio-frequency output-transformer

68, from the secondary of which latter the intelligence received by the receiving-apparatus may be tapped off to a loud-speaker or other translating-device.

Returning now to the beat-frequency-detecting or heterodyne-detecting unit 61ac, it will be noted by reference to Fig. 2 that one of the inputs of the said unit 61ac is connected to the output of an amplifying-unit 67, while the other input of the said unit 61ac, is connected to one of the outputs of the inductive-coupling unit 59c.

The output of the beat-frequency-detecting or heterodyne-detecting unit 61ac is inductively coupled to an amplitude-limiting unit 69. In turn, the output of the amplitude-limiting unit 69 is connected to the input of a frequency-modulator 70, which latter has its output connected to an amplifying-unit 71. The output of the amplifying-unit 71 just referred to is connected to the input of an amplifying-unit 72, which latter has its output connected to the input of the wave-generating unit 54c before referred to.

The various units 54c to 72 inclusive, above referred to, will now be described in sufficient detail to enable their respective functionings to be understood.

The receiving-antenna 11ab is connected to the control-grid of a pentode electronic-tube generally designated by the reference character 13 forming a feature of the amplifying-unit 67. The said tube 13 includes also a screen-grid and a suppresser-grid, as well as a plate, which latter is connected to a primary inductance-coil 74. The primary inductance-coil 74 just referred to cooperates with two secondary inductance-coils 75 and 76 forming features of the beat-frequency-detecting or heterodyne-detecting unit 61ac. Each of the said secondary inductance-coils 75 and 76 has respectively connected across it one of two variable condensers 77 and 78. Each of the said condensers acts in conjunction with its complemental inductance-coil to provide a resonant-circuit. The two inductance-coils 75 and 76 are connected in series with the control-grid of a pentode electronic tube 79 forming a feature of the unit 61ac.

The tuned circuit in which the secondary inductance-coil 75 and its complemental condenser 77 are included, is resonant to a frequency widely different from the resonant-frequency of the circuit in which the coil 76 and condenser 78 are included. Therefore, the primary inductance-coil 74 is so constructed and proportioned as to pass the two frequencies to which the circuits of the secondary coils 75 and 76 are respectively responsive.

The beat-frequency-detecting unit 61ac also includes a primary inductance-coil 80 cooperating with a secondary inductance-coil 82. The said secondary inductance-coil is connected in series with the cathode and suppresser-grid circuit of the tube 79. The primary inductance-coil 80 is connected to one of the outputs of the inductive-coupling unit 59c, for purposes as will hereinafter appear. The plate of the tube 79 is connected to a primary inductance-coil 83.

The primary inductance-coil 83 of the unit 61ac cooperates with two secondary inductance-coils 84 and 85 forming features of the amplitude-limiting unit 69. Each of the said secondary inductance-coils 84 and 85 has respectively connected across it one of two variable condensers 86 and 87, each of which latter acts in conjunction with its complemental inductance-coil to provide a resonant-circuit.

The tuned circuit in which the secondary inductance-coil 84 and the condenser 86 are included, is resonant to a frequency widely different from the resonant frequency of the circuit in which the coil 85 and condenser 87 are included. The primary inductance-coil 83 is, therefore, constructed and arranged to pass the two frequencies to which the circuit of the secondary coils 84 and 85 are respectively responsive.

The circuit of the elements 84-86 of the unit 69 includes one of the plates of a twin diode electronic tube 88, while the circuit in which the elements 85 and 87 are located is connected to the other of the plates of the said tube.

It may here be noted that the resonant-circuit in which the elements 84-86 are included, develops a voltage which is opposite to the voltage developed by the energy in the resonant-circuit of which the elements 85-87 form a part. These opposed voltages appear alternately at the output of the unit 69 and are applied to the grid of a gas-filled triode electronic tube 89 forming a feature of the frequency-modulator 70.

In addition to the gas-filled triode 89, the frequency-modulator 70 also includes the usual resistors and a complemental variable condenser as shown, to thus produce an output-wave having saw-tooth or logarithmic characteristics. The frequency-modulator 70 also includes a condenser 89d and a push-button switch 89e, all in series with the cathode-plate circuit of the tube 89.

As before noted, the output of the frequency-modulator 70 is connected through a variable resistor and a variable condenser to the input of the amplifying-unit 71. The amplifying-unit 71 includes a pentode electronic-tube 90 having its control-grid connected to the output of the frequency-modulator 70. The output of the amplifying-unit 71 is connected to the input of the amplifying-unit 72 before referred to.

The amplifying-unit 72 just above referred to includes a triode electronic-tube 91 having its cathode constituting the output of the amplifying-unit 72 and connected to the input of the wave-generator 54c before referred to.

The wave-generator 54c includes a triode electronic-tube generally designated by the reference character 92, which is here used as a super-regenerative detector or blocking-oscillator tube in a manner well understood in the art. The adjuncts of the tube 92 are schematically represented in Fig. 2 and do not require detailed description other than to mention that it is the cathode of the tube 92 which is connected to the output of the amplifying-unit 72. The plate-circuit of the tube 92 is connected to the high-pass filter 55c before referred to, which latter, in turn, is connected to the input of the amplifying-unit 56c.

The amplifying-unit 56c includes a pentode electronic-tube generally designated by the reference character 93, and having its control-grid circuit connected to the output of the high-pass filter 55c. Here again, the adjuncts of the amplifying-unit 56c do not require detailed description other than to note that the plate-circuit of the tube 93 is made resonant by the inclusion of a condenser 94 and a primary inductance-coil 95.

The primary inductance-coil 95 of the amplifying-unit 56c cooperates with a secondary inductance-coil 96 constituting the input feature of the combined rectifying-and-amplifying unit 57c. The coil 96 just referred to, in conjunction with a condenser 97, provides a resonant-circuit

connected across the diode-section of a combined diode-triode electronic-tube generally designated by the reference character 88. The output of the resonant-circuit which includes the elements 88 and 97, is connected to the grid of the triode-section of the tube 88, while the load-resistor 89 and associated condenser 100 of the diode-section, are connected to the cathode of the tube 88 through a biasing-battery 101. The said biasing-battery serves to impose a bias-voltage on the grid of the triode-section of the combination tube 88. The plate-circuit of the triode-section of the tube 88 includes an inductance-coil 102.

The inductance-coil 102 of the unit 57c constitutes the output element of the said unit 57c and is connected to the input of the band-pass filter 58c before referred to. The output of the band-pass filter 58c is connected through a condenser 103 to a primary inductance-coil 104. Both the condenser 103 and the inductance-coil 104 may be considered to constitute features of the inductive-coupling unit 58c before referred to. The primary inductance-coil 104 cooperates with two secondary inductance-coils respectively designated by the reference characters 105 and 106 and also forming features of the unit 58c. The said secondary inductance-coil 106 is connected to the primary inductance-coil 80 of the beat-frequency-detecting unit 61ac, while the remaining secondary inductance-coil 105 of the unit 58c is connected to a primary inductance-coil 107 forming a feature of the beat-frequency-detecting or heterodyne-detecting unit 60bc.

The primary inductance-coil 107 just above referred to cooperates with a secondary inductance-coil 108 also forming a feature of the said unit 60bc. One terminal of the coil 108 is connected to ground through a bias-resistor 109 and a condenser 110. The other terminal of the secondary inductance-coil 108 is connected to the cathode of a pentode electronic tube 111, which has its suppresser-grid-connected to the other or first-mentioned terminal of the secondary inductance-coil 108. The resonant plate-circuit of the tube 111 includes a condenser 112 and a primary inductance-coil 113.

The primary inductance-coil 113 above referred to, constitutes the output-feature of the beat-frequency-detecting unit 60bc and cooperates with a secondary inductance-coil 114 constituting the input-feature of the amplifying unit 62. The said secondary inductance-coil 114, together with its complemental condenser 115, provides a resonant-circuit for the control-grid of a pentode electronic tube generally designated by the reference character 116, and forming a feature of the unit 62. The remaining adjuncts of the unit 62 do not require detailed description herein, other than to note that the output of the said unit includes a primary inductance-coil 117 and a complemental condenser 118 connected to the plate of the tube 116 and providing a resonant-circuit for the output of the said tube.

The primary inductance-coil 117 of the amplifying-unit 62 cooperates with a secondary inductance-coil 119 forming the input-feature of the combination rectifying-and-amplifying unit 63. The said secondary inductance-coil is complemented by a condenser 120 and together therewith provides a resonant-circuit for the diode-section of a diode-triode electronic tube generally designated by the reference character 121 also forming a feature of the unit 63. The control-grid of the triode-section of the tube 121 obtains

its bias in a manner well understood in the art from a suitably-connected battery 122, as is clearly indicated in Fig. 2. The plate of the triode-section of the diode-triode tube 121 is connected to the primary inductance-coil of the audio-frequency transformer 64. The secondary inductance-coil of the transformer 64 is connected to the control-grid circuit of a pentode electronic tube 123 of the audio-frequency amplifier 65 before referred to. The remaining adjuncts of the amplifier 65 do not require detailed description herein, though it is to be noted that the plate of the said tube 123 is connected to the primary inductance-coil of the audio-frequency output-transformer 66. The terminals of the secondary inductance-coil of the transformer 66 may be connected to a loud-speaker or other suitable electrical translating-device.

In conjunction with the apparatus above described for producing the typical wave C, three batteries or other suitable sources of electrical energy 124, 125 and 126 are employed. In the particular instance shown, the battery 124 serves to supply the heaters of the various electronic tubes, while the battery 125 is suitably connected to such of the various electronic tubes as include a screen-grid, to impress a suitable intermediate voltage on such screen-grids. The battery 125, in conjunction with the battery 126, is connected to the respective plates of the various electronic tubes with the exception of the twin diode plates of the tubes 88, 89 and 121.

THE EVOLUTION OF A TYPICAL WAVE C

For purposes of clarity of description, let it be assumed that the frequency-modulated wave C has a band-width having a lower-frequency limit of 1,500 kilocycles and an upper-frequency limit of 2,500 kilocycles.

Under the circumstances above outlined, the wave-generator 54c (which is a self-blocking super-regenerative detector or oscillator) will be constructed and arranged to produce a fundamental-wave having a fundamental-frequency of 25 kilocycles, together with the harmonic-frequencies thereof, which latter have pronounced values. This fundamental-frequency will, however, be frequency-modulated by the frequency-modulator 70 so as to result in recurrent groups of waves, each corresponding to the others in both pattern and time-interval, and all of which groups occur between an upper frequency-limit of 25 kilocycles and a lower frequency-limit of 19.36 kilocycles. The resultant frequencies between the limits just referred to, represent the rate of quenching or suppression of the wave-generator 54c. The harmonic-frequencies of the aforesaid fundamental-frequency will also be frequency-modulated by the frequency-modulator 70.

Under the particular circumstances above described, the frequency-modulator 70 will have an output-frequency of 10 kilocycles, in order to contribute to, jointly with the wave-generator 54c, the frequency-modulated characteristics of the wave C. Furthermore, the output of the frequency-modulator 70 is characterized by a logarithmic or saw-tooth wave-form (rather than a sinusoidal wave-form) having the time of its rise corresponding to the time of its decline, to thus correspond in this respect to the output of the frequency-modulator 28ab of the transmitting system (Fig. 1). As before noted in producing a logarithmic or saw-tooth wave-form, the said wave-form is kept as near to linear rise and de-

cline respectively as is feasible. Here again, such linear characteristics enable the present system to operate with maximum facility though they are not essential.

It is well at this point to here note the function of the amplitude-limiting unit 69. This unit 69 serves to limit the amplitude of the output of the frequency-modulator 70 in order to hold the frequency-limits of the wave C at predetermined values.

Before returning to the wave-generator 54c, it is also well at this point to call attention to the functioning of the amplifying-unit 67 and the beat-frequency-detecting or heterodyne-detecting unit 61ac.

The amplifying-unit 67 serves to amplify the waves received by the receiving-antenna 11ab and to amplify the same (without discrimination) and supply the said waves in amplified form to the primary inductance-coil 14 of the amplifying-unit 67 for transfer to the respective secondary inductance-coils 15 and 16 forming features of the beat-frequency-detecting unit 61ac.

Briefly stated, the function of the beat-frequency-detecting or heterodyne-detecting unit 61ac is to cause the upper and lower frequency-limits of each cycle of frequency-modulation of each of the waves A, B and C to coincide or be synchronized.

The series-connected secondary inductance-coils 15 and 16 of the unit 61ac are respectively tuned by means of their condensers 71—78, to the upper frequency-limit (1800 kilocycles) and the lower frequency-limit (900 kilocycles) of the wave A. It is to be explained in this connection, that while both the waves A and B are impressed upon the series-connected secondary inductance-coils 15 and 16, the respective resonant characteristics of the circuits of which they form a part are such as to respond only to narrow bands respectively just below the upper and just above the lower frequency-limits of the wave A. This arrangement is, as stated, for the reason that the wave A has arbitrarily been chosen as a control-wave, which functions in a manner as will hereinafter be described. Wave B, while rejected for the most part by the unit 61ac, is utilized by the unit 60bc in a manner as will also hereinafter appear.

The unit 61ac rejects all of wave B except for the small part thereof, which comes into momentary resonance with that one of the resonant circuits of the unit 61ac which is tuned to about 1,800 kilocycles.

The frequencies of 1800 kilocycles and 900 kilocycles before referred to and representing the respective frequency-limits of the wave A, are impressed upon the control-grid of the tube 19. The band of frequencies represented by the wave C, namely, those between 1500 kilocycles and 2500 kilocycles inclusive, will be impressed upon the suppresser-grid of the tube 19. Rectification of all of these frequencies will occur and there will be impressed upon the plate of the said tube 19, for application to the primary inductance-coil 83, what amounts in effect to two new waves appearing alternately and one having a frequency substantially at 600 kilocycles and the other having a frequency substantially at 700 kilocycles.

In other words, the unit 61ac has mixed or heterodyned the characteristics of both the wave A and the wave C to produce the two alternately-appearing waves above referred to, respectively having frequencies substantially at 600 kilocycles and 700 kilocycles.

Let it be assumed that the resonant network in which the elements 84 and 86 of the unit 88 are included is resonant to a frequency of 700 kilocycles, and that the resonant network of which the elements 85 and 87 form parts, is resonant to a frequency of 600 kilocycles. The connections within the unit 69 are such that at one instant the circuit of one of the two diode-plates has periodically impressed thereon a negative voltage, while the circuit of the other diode-plate has periodically impressed thereon a positive voltage alternately with respect to the appearance of negative voltages in the circuit of the first-mentioned diode-plate.

15 The alternating negative and positive voltages above referred to are both impressed upon the control-grid of the gas-filled triode-tube 89 of the frequency-modulator 70 and provide the timing impulses for actuating the charge- and discharge-characteristics of the said tube 89.

20 As before noted, the frequency-modulator 70 includes a condenser 89d and a push-button switch 89e. These features are provided to initially effect the synchronization of the waves A, B and C. This effect is achieved by closing the push-button switch 89e to cut in the condenser 89d and thereby slightly change the frequency characteristics of the frequency-modulator 70. The retention of the push-button switch 89e in a 25 closed position for a matter of a second or two will serve the purpose of effecting initial synchronization between the aforesaid waves A, B and C, and upon the release or opening of the said push-button switch 89e the inherent characteristics of the system will assert themselves and maintain the synchronization or coincidence of the said waves.

25 As before noted, the normal output of the frequency-modulator has a frequency of 10 kilocycles, which is applied in amplified values through the amplifying-units 71 and 72 to the cathode circuit of the tube 92 of the wave-generating unit 54c.

30 Also as before noted, the output of the wave-generating unit 54c will be a fundamental-wave having a fundamental-frequency of 25 kilocycles together with the harmonic-frequencies thereof. The fundamental-frequency just referred to, together with the harmonics thereof, will be frequency-modulated by the frequency-modulator 70, so that the output of the wave-generating unit 54c is, in effect, recurrent groups of waves between an upper frequency-limit of 25 kilocycles and a lower frequency-limit of 19.36 kilocycles.

35 Under the particular set of conditions here being considered, the characteristics of the high-pass filter 55c will be such as to cause the maximum attenuation of all frequencies below about 8325 kilocycles in value which is inclusive of the aforesaid group of fundamental-waves appearing at the output of the wave-generating unit 54c. The characteristics of the said filter will also be such as to cause the minimum attenuation of all of the frequencies at and above about 8325 kilocycles. The net result will be that at the output of the high-pass filter 55c, the frequencies at and above about 8325 kilocycles in value will appear with sufficient value to be employed in the subsequent steps of the receiving system, whereas frequencies below about 8325 kilocycles will have negligible values and will not affect subsequent steps of the receiving system.

40 The output of the high-pass filter will be supplied to the amplifying-unit 56c. This ampli-

fying-unit, as before noted, has a resonant network which includes the elements 94 and 95 which, in conjunction with the resonant network (including the elements 96 and 97) of the combined rectifying-and-amplifying unit 51c, will freely pass only the selected frequency which, in this instance, will be a relatively-narrow band centered at about 8325 kilocycles. Here again, it may be noted, as is well known in the art, frequencies other than the selected frequencies of about 8325 kilocycles, will pass from the unit 56c to the unit 51c, but in such negligible amplitude as not to affect the following stages of the receiving system.

With the particular values now being considered, the group of frequency-modulated harmonic-frequencies extending between and including the 333d to the 430th will successively appear in the resonant network comprising the elements 94 and 95 of the unit 56c, and the elements 96 and 97 of the unit 51c. As each of the aforesaid frequency-modulated harmonic-frequencies (ninety-seven in number) successively appears in the resonant network just referred to, each will at some point in the cycle of its frequency-change come into resonance (about 8325 kilocycles) with the aforesaid resonant network, and will while in substantial resonance, cause an increment of energy to appear in the said resonant network. Owing to their frequency-modulated character, the time-intervals between the respective maximum values of the said increments of energy will vary. This variation in time-intervals results from the fact that the different harmonic-frequencies of the aforesaid fundamental-wave progressively vary arithmetically in time-interval. Thus, the time-interval between the 333d and the 334th harmonics may for convenience of illustration be considered to be equal to $1/333$, in which case the relative time-interval between the 334th and the 335th harmonics will be smaller and equal to $1/334$, and so on, to the 429th and 430th harmonics, which will have a still smaller relative time-interval of $1/429$. It is this arithmetical progression or relationship which determines the ultimate frequency-modulation characteristics of the wave C.

The radio-frequency components of each of the increments of energy just above referred to will vary in amplitude and the said increments will occur in groups of ninety-seven, which groups provide what is commonly known in the art as a "wave-envelope."

The radio-frequency waves representing each of the aforesaid increments of energy, are rectified by the diode-section of the tube 98 of the unit 51c, with the result that half of each of the said waves and half of the envelope thereof are eliminated. The remaining halves of the said waves are so filtered by the load resistor 99 and its complemental condenser 100 that there appears (amplified) in the output of the triode section of the tube 98, a new frequency-modulated fundamental-wave having frequency-limits respectively at 1500 kilocycles and 2500 kilocycles, together with a series of harmonic-waves representing harmonics of all of the waves occurring between the said limits of 1500 kilocycles and 2500 kilocycles inclusive.

It may be here shown, by example, through one cycle of operation, how the output of the unit 70, in conjunction with the operation of blocking oscillator 54c and the tuned network comprising the elements 94, 95, 96 and 97 which is tuned to a relatively narrow band centered on 8325 kilo-

cycles, as well as the rectifying network in which the elements 96 and 97 are included, contribute to the creation of the new frequency-modulated wave C appearing across the diode-load-resistor 99 and its complemental condenser 100.

It may be assumed, for purposes of illustration, that at times t_0 , the amplitude of the output of unit 70 as represented by the bias developed through the cathode resistor paralleling tubes 91 of amplifying unit 72 and tube 92 of blocking oscillator 54c is $E_c + 0$, and the output of oscillator 54c is a function having a fundamental frequency of 19.3604 kilocycles.

It may be further assumed that the frequency output of unit 70 is, as shown above, 10.0 kilocycles per second.

A further assumption, for purposes of illustration, is that the rising function of the output of the unit 70, which equals X , and the declining function which equals $1 - X = Y$ represent straight lines. This assumption is permissible since in practical cases the logarithmic rise and decline of a saw-tooth wave can be made to approach linearity sufficiently to support the illustration.

A still further valid assumption is that the frequency variation of the output of oscillator 54c is linear with the rise and decline of the function of the unit 70 output, since the actual logarithmic variation of the frequency of the 54c oscillator output, with the variation of bias voltage across the tube 92 cathode resistor can be made to approach linearity sufficiently to support the illustration.

The fundamental frequency of 19.3604 kilocycles, at the output of oscillator 54c, has a large number of higher order harmonic frequencies harmonically spaced in frequency, so that the second harmonic has a frequency of 38.7208 kilocycles, the third harmonic has a frequency of 58.0812 kilocycles, etc. It can be seen therefore, that the 430th harmonic has a frequency of, substantially, 8.325 kilocycles, and is, therefore, in resonance with the tuned network comprising the elements 94, 95, 96 and 97. In consequence, the voltage developed across the element 99, which, together with its complemental condenser 100, forms the load network of the diode rectifier of the tube 98, is at maximum.

At time t_1 , the amplitude of the output of unit 70 is $E_c + .025$ volt, and the output of blocking oscillator 54c has changed, as a result of the change in bias voltage, to 19.383 kilocycles. The frequency of the 430th harmonic is now 8.334.69 kilocycles, and is therefore substantially out of resonance with the tuned network comprising elements 94, 95, 96 and 97. And, since the 429th harmonic has a frequency of 8.315.3. kilocycles it, too, is substantially out of resonance with the tuned network, comprising elements 94, 95, 96 and 97. As a result the voltage developed across the diode load resistor 99 is at a minimum.

At time t_2 , the amplitude of the output of unit 70 is such as to develop a bias of $E_c + .05$ volt across the tube 92 cathode resistor, and the output of blocking oscillator 54c is now 19.4055 kilocycles, as a result of this further change in bias. The 430th harmonic is now further out of resonance while the 429th harmonic has come into substantial resonance with the tuned network comprising the elements 94, 95, 96 and 97, and the voltage developed across the diode-load-resistor 99 is again at maximum.

It can be seen from the description above, that from time t_0 to time t_2 the voltage developed across the diode-load-resistor 99 has described a

function which possesses a decline for the period from time t_0 to time t_1 , and a rise from time t_1 to time t_2 . And the decline, together with the rise, constitute a wave function which can be mathematically resolved into a fundamental sine wave, plus a large number of sine wave harmonics of the said fundamental sine wave.

It may be convenient to further inspect the successive values involved in this example by means of the following table in which the first column heading "Time" indicates the progress of time from t_0 to t_n , while the function of the output of unit 70 is rising from zero to maximum, and from t_n to t_{n+1} , while the function is declining from maximum to zero again, this representing one cycle in the operation of the unit 70.

Table

Time	Effect on 94 Bias by 70 Output (Volts)	Freq. Output of Osc. 54c (Kc.)	Harm. at Reson. (8325 Kc.)	Harms. near Reson. (8325 Kc.)	Freq. of Harm. at Reson. (Kc.)	Freq. of Harms. Near Reson. (Kc.)	Voltage Across Load Re- sistor 99
t_0	$E_c + 0.0$	19.3604	430th		8,325		Maximum.
t_1	$E_c + 0.25$	19.383		430-429	8,325	8,334-8,315	Minimum.
t_2	$E_c + 0.5$	19.4055	429th		8,325		Maximum.
t_3	$E_c + 0.75$	19.4292		429-428	8,325	8,335-8,315	Minimum.
t_4	$E_c + 1.0$	19.4509	428th		8,325		Maximum.
t_5	$E_c + 1.40$	24.8507	335th		8,325		Do.
t_6	$E_c + 1.71$	24.8878		335-334	8,325	8,337-8,312	Minimum.
t_7	$E_c + 1.74$	24.9251	334th		8,325		Maximum.
t_8	$E_c + 1.77$	24.9625		334-333	8,325	8,337-8,312	Minimum.
t_9	$E_c + 1.80$	25.00	333d		8,325		Maximum.
t_{10}	$E_c + 1.77$	24.9625		333-334	8,325	8,312-8,337	Minimum.
t_{11}	$E_c + 1.74$	24.9251	334th		8,325		Maximum.
t_{12}	$E_c + 0.25$	19.383		429-430	8,325	8,315-8,334	Minimum.
t_{13}	$E_c + 0.0$	19.3604	430th		8,325		Maximum.

By examining the above table it can be seen that from t_0 to time t_2 , the voltage on the load resistor 99 varies from maximum when the 430th harmonic is in resonance with the tuned network comprising elements 94, 95, 96 and 97, through minimum when the harmonic nearest the resonance frequency of the tuned network are out of resonance, and back to maximum when the 429th harmonic is in resonance with the tuned network. This represents one complete cycle of a wave function having a period equal to the time interval from t_0 to t_2 .

Since, as has been noted, the frequency of the output of unit 70 is 10.0 kilocycles per second, and the time of the rising function of the 70 output represents one-half cycle of operation, the time t_0 to t_n is $1/20,000$ second.

And, since the output of oscillator 54c is 19.3604 kilocycles at time t_0 , and 25.0 kilocycles at time t_n , the variation in frequency in $1/20,000$ second is 5.6396 kilocycles.

The variation in frequency of the oscillator 54c output from time t_0 to time t_2 is 19.4055 minus 19.3604 equals .0451 kilocycle and, since the frequency variation during $1/20,000$ second is 5.6396 kilocycles the time interval represented by t_0 to t_2 is $.0451/5.6396 \times 0.00005$ equals $.00000039985$ second.

It can be seen, therefore, that if the function of the wave developed by the voltage across the diode-load-resistor 99 during the time t_0 to t_2 were recurrent, the frequency of that function would be 2,500.9 kilocycles. This frequency is substantially near one frequency limit (2500 kc.) of the wave C, as shown in this disclosure.

To determine the frequency of the voltage wave-function developed across the load-resistor 99, during the time interval t_2 to t_4 we have a frequency differentiation in the oscillator 54c output of .0454 kilocycle, and, since the frequency variation during $1/20,000$ second is 5.6396 kilo-

cycles the time interval represented by t_2 to t_4 is $.0454/5.6396 \times 0.00005$ equals $.00000040251$ second.

It is seen, therefore, that if the wave-function developed by the voltage across the diode-load-resistor 99 during the time interval t_2 to t_4 were recurrent, the frequency of the wave-function would be 2,484.4 kilocycles. The frequency of that wave-function during the interval t_2 to t_4 is therefore 16.5 kilocycles lower than the wave-function during the previous interval t_0 to t_2 .

It may not be necessary to show, individually, the 97 successive voltage wave-functions appearing across the diode-load-resistor 99 during the successive time intervals t_4 to t_6 , t_6 to t_8 , etc., up to t_{n-4} to t_{n-2} , since it is apparent that in the interval t_4 to t_{n-4} , the curve of frequency variation of

35 wave-functions developed across the diode-load-resistor 99 is downward, until the interval t_{n-4} to t_{n-2} .

Returning to the table it can be seen that the frequency differentiation of the oscillator 54c 40 output for the interval t_{n-4} to t_{n-2} , is .0744 kilocycle and since the frequency variation during $1/20,000$ second is 5.6396 kilocycles the time interval represented by t_{n-4} to t_{n-2} is $.0744/5.6396 \times 0.00005$ equals $.00000065961$ second. The wave-function occurring during the interval t_{n-4} to t_{n-2} would, if it were recurrent, have a frequency of 1,516 kilocycles.

In a similar manner, the frequency differentiation of the oscillator 54c output for the interval t_{n-2} to t_n , shown in the table, is .0749 kilocycle and the time interval represented, therefore, is $.0749/5.6396 \times 0.00005$ equals $.00000066405$ second.

This wave-function would, if it were recurrent, have a frequency of 1,505.9 kilocycles, and this is substantially near the lower limit frequency (1500 kc.) of the wave C as shown in the disclosure.

The interval t_n to t_{n+2} , shown in the table is the same as the interval t_{n-2} to t_n , for, while the period from t_0 to t_2 represents the rising function of the output of the unit 70, the period from t_n to t_{n+2} represents its declining function. The frequencies occurring during the period t_n to t_{n+2} are the same as those occurring during the period t_0 to t_2 , but occur in reverse order. Thus, the frequency variation from time t_0 to time t_n is from 2500.9 kilocycles to 1505.9 kilocycles, and the frequency variation from time t_n to time t_{n+2} is from 1505.9 kilocycles to 2500.9 kilocycles.

This new fundamental-wave, together with its harmonic-waves, will appear in the primary inductance-coil 102 of the unit 57c, and will be applied to the input of the band-pass filter 58c.

The band-pass filter 58c is designed and adapted to so attenuate the harmonic-waves sup-

plied to it as to render them negligible in value at the output of the said filter, whereas, the fundamental-wave having frequency-limits between 1500 kilocycles and 2500 kilocycles inclusive, will pass with minimum attenuation and will be applied to the primary inductance-coil 104 of the inductive-coupling unit 59c.

The frequency-modulated fundamental-wave above referred to and having frequency-limits between 1500 kilocycles and 2500 kilocycles respectively, will be coincidentally impressed upon both of the secondary inductance-coils 105 and 106 by the primary inductance-coil 104 of the unit 59c. The secondary inductance-coil 106 will apply this fundamental-wave to the primary inductance-coil 88 of the unit 61ac, while the secondary inductance-coil 105 will through the connecting circuit, apply the said fundamental-waves to the primary inductance-coil 107 of the beat-frequency-detecting or heterodyne-detecting unit 60bc. The effect of the aforesaid fundamental-wave within the unit 61ac has already been described, and the effect of the said wave within the unit 60bc will now be described.

The band of frequencies represented by the wave C, namely, those between 1500 kilocycles and 2500 kilocycles inclusive, will be transferred by the primary inductance-coil 107 of the unit 60bc to the secondary inductance-coil 108 thereof, and will be thereby impressed upon the cathode and suppressor-grid circuit of the tube 111. Coincidentally, both the waves A and B will be impressed upon the control-grid of the said tube 111 which is connected to the receiving-antenna 11ab though the wave A will not be utilized, since, as before described, it is at this time being utilized in the unit 61ac. Therefore, as far as the unit 60bc is concerned, the wave A need not be considered.

The band of frequencies between the respective limits of 1000 kilocycles to 2000 kilocycles, representing the wave B, are impressed upon the control-grid of the tube 111, while the band of frequencies representing the wave C, namely, those between 1500 kilocycles and 2500 kilocycles inclusive, will be impressed upon the suppressor-grid of the tube 111. Rectification of all of these frequencies will occur and there will be impressed upon the plate-circuit of the said tube 111, for application to the circuit of the primary inductance-coil 113, what amounts, in effect, to a new amplitude-modulated wave (without frequency-modulation) having a frequency substantially at 500 kilocycles.

Stated briefly, it may be said that the beat-frequency-detecting or heterodyne-detecting unit 60bc has mixed or heterodyned the characteristics of both the wave B and the wave C to produce a new relatively-narrow band of amplitude-modulated waves having substantially no frequency-modulation characteristics and centered substantially at 500 kilocycles.

Let it be assumed that the resonant network in which the elements 112 and 113 of the unit 60bc are included, and the resonant network in which the elements 114 and 115 of the unit 62 are included, is resonant to a frequency of about 500 kilocycles. This amplitude-modulated wave will be applied to the control-grid of the tube 116 of the amplifying-unit 62. It is to be understood in this connection, however, that the resonant network in which the elements 112 to 115 inclusive are included is, as is well understood in the art, so characterized as to allow the passage

of the side-frequencies incident to the amplitude-modulations referred to.

The aforesaid amplitude-modulated wave of about 500-kilcycle frequency, is applied to the plate-circuit of the tube 116 of the amplifying-unit 62 and will be transferred by the primary inductance-coil 117 to the twin diode-section of the diode-triode tube 121 of the combined rectifying-and-amplifying unit 63. The composite resonant network in which the elements 117, 118, 119 and 120 are included, has resonance characteristics corresponding to those of the composite resonant network in which the elements 112, 113, 114 and 115 are included. The aforesaid amplitude-modulated wave having a frequency of about 500 kilocycles, will be rectified by the diode-section of the tube 121 of the unit 63, with the result that half of the said wave and half of the envelope thereof will be eliminated. The remaining half of the said wave is so filtered by the load-resistor which is in series with the diode-section of the tube 121 and its complementary condenser, that there appears on the control-grid of the triode-section of the diode-triode tube 121, the reconstructed intelligence which has been applied to the input of the signal-input unit 19ab of the transmitting system of Fig. 1.

The aforesaid reconstructed intelligence is applied to the primary inductance-coil of the audio-frequency transformer 64 and is transferred, of course, to the secondary inductance-coil thereof, and by the latter impressed upon the control-grid circuit of the tube 123 of the audio-frequency amplifier 65. The reconstructed intelligence in amplified values is now applied to the primary inductance-coil of the audio-frequency output-transformer 66. The said reconstructed intelligence is transferred by the primary inductance-coil of the unit 66 to the secondary inductance-coil thereof, and may be taken off from the terminals of the said secondary inductance-coil to a loud-speaker or other suitable translating-device.

THE RELATIONSHIP OF THE WAVE C TO THE WAVES A AND B

As before noted in connection with the doubly-modulated waves A and B, the intelligence respectively imposed thereon is so distorted as to render its reception by unauthorized persons extremely difficult. This distortion is due to the phase-displacement existing between the respective amplitude-modulations impressed upon the said waves by the intelligence being transmitted.

In the receiving system of Fig. 2, both of the waves A and B are received, but the intelligence carried by the wave B alone will be reconstructed. The said doubly-modulated wave B with the intelligence carried thereby (which latter is due to the amplitude-modulation), will be received by the unit 60bc in the manner of a more or less conventional superheterodyne receiver and caused to heterodyne with the singly-modulated wave C. The resultant wave is rectified as before described, and the intelligence brought in by the wave B is reconstructed and appears at the output of the audio-frequency output-transformer 66.

The intelligence arriving with the wave B is reconstructed under the control of the locally-generated wave C, which latter has evolved in turn, under the control of the wave A. The wave A, as before noted, has been diverted to the beat-frequency-detecting or heterodyne-detecting unit 61ac.

In Fig. 3 is schematically represented the relative frequency-modulation characteristics of the waves A, B and C when, as preferred, the said waves A and B are in phase-opposition or, in other words, at maximum phase-differentiation insofar as the amplitude-modulation characteristics are concerned. Wave C as before noted, is not doubly-modulated, as are the waves A and B, but merely single-modulated by having frequency-modulation characteristics.

By reference to Fig. 3, it will be seen that the respective lower frequency-limits of the waves A and B are 100 kilocycles apart on the frequency-spectrum, whereas, the respective upper frequency-limits of the said waves are 200 kilocycles apart. Furthermore, it will be noted that the upper frequency-limit of the wave C is 700 kilocycles above the upper frequency-limit of the wave A and 500 kilocycles above the upper frequency-limit of the wave B.

It will further be noted by reference to Fig. 3 that in the particular wave-relationships previously described, the lower frequency-limit of the wave C is 600 kilocycles above the lower frequency-limit of the wave A and 500 kilocycles above the lower frequency-limit of the wave B.

It will be noted further by reference to Fig. 3 that the relationship between the waves B and C is such that a constant frequency-difference exists, whereas, as between the waves A and B, a variable frequency-difference exists.

The aforesaid constant frequency-difference between the respective limits of the waves B and C is utilized in the receiving system to extract the intelligence from the wave B by a substantially conventional superheterodyne method.

On the other hand, the variable frequency-difference existing between the waves A and B is made use of in the receiving system to effect the synchronizing of the phase of the respective frequency-modulation cycles of the waves A, B and C.

The various waves A, B and C may obviously have a widely different relationship from those above described, such for instance as:

Lower Frequency-Limits of Frequency-Modulation (Kilocycles)	Upper Frequency-Limits of Frequency-Modulation (Kilocycles)
1 A=1000, B=1000, C=1500	A=1800, B=2000, C=2500
2 A=900, B=1000, C=1500	A=1800, B=1800, C=2300
3 A=800, B=1100, C=1600	A=1400, B=2100, C=2600
4 A=1800, B=2000, C=2400	A=3600, B=4000, C=4400
5 A=900, B=1000, C=1300	A=1800, B=1500, C=1800
6 A=800, B=1000, C=900	A=1600, B=1900, C=1800

The side-bands occasioned by the frequency-modulation of the transmitted waves A and B (as well as wave C) through the width of the relatively-wide selected spectrum, are individually of negligible value and do not individually affect the receiving apparatus, since the index of frequency-modulation is too high. The individual side-bands incident to the amplitude modulation of the waves A and B, are also negligible in value because amplitude-modulation imposed upon a frequency-modulated wave has substantially the same effect as amplitude-modulation imposed upon individual side-bands.

However, as is well known in the art, the side-bands above referred to, while individually of negligible value, add up vectorially to the instantaneous-value of the waves A and B which do affect the receiving-apparatus of Fig. 2.

THE DOUBLE-FREQUENCY-MODULATION OF THE CARRIER-WAVES A AND B

The waves A and B as previously described were doubly-modulated in the sense that each thereof was frequency-modulated and amplitude-modulated. It will be here shown, however, that each of the waves A and B may be doubly-frequency-modulated.

To effect the double-frequency-modulation of the waves A, an apparatus like that illustrated in Fig. 4 may be employed. The apparatus of Fig. 4 corresponds to the apparatus illustrated in Fig. 1 with the exceptions below noted, so that in the main the description of the elements shown in Fig. 1 apply with equal force to the similar elements shown in Fig. 4.

In Fig. 4, it will be noted that the band-pass filter 17b is set to pass a wave having different frequency-limits from the wave passed by the band-pass filter 17b as set forth in Fig. 1. Furthermore, there is added to the apparatus a signal-input unit 128ab. The said unit 128ab includes a transformer comprising a primary-winding 129 and a complementary secondary-winding 130. Adjacent the primary-winding 129 is a switch 131 by means of which the said primary-winding may be cut into or out of circuit, as may also be the primary-winding of the signal-input unit 19ab.

The wave-generating unit 12a of Fig. 4 has added thereto a by-pass condenser 132a which is interposed in the ground-connection of the grid-coil of the tube 35a. Similarly, there has been added to the wave-generating unit 12b of the structure of Fig. 4, a by-pass condenser 133b which is interposed in the ground-connection of the grid-coil of the tube 35b.

By reference to Fig. 4 it will be seen that the grid-coil of the tube 35a of the wave-generating unit 12a is connected to one terminal of the secondary-winding 130 of the signal-input unit 128ab, while the opposite terminal of the said secondary-winding is connected to the grid-coil of the tube 35b of the wave-generating unit 12b.

THE EVOLUTION OF TYPICAL DOUBLE-FREQUENCY-MODULATED WAVES A AND B

The voice or other intelligence to be transmitted will be applied to the two terminals of the primary-winding 129 of the signal-input unit 128ab. However and for a better functioning of the apparatus, the intelligence may be viewed as not being yet applied and the creation of the basic-frequency-modulation (Fig. 5) of the carrier-wave A may first be described. It may here be noted that except for relative bandwidths, the basic frequency-modulation of the wave B will follow the same general pattern as that of the wave A.

Reference may be had to the full line shown in Fig. 8 as indicative in a schematic sense, of the basic frequency-modulation of the wave A, to be supplemented by an additional frequency-modulation (provided by the signal-input) which results in the double-frequency-modulated wave A illustrated by the broken line in Fig. 8.

The creation and basic frequency-modulation (the full line of Fig. 8) of the wave A will be the same as that described in connection with the creation of the basic frequency-modulated wave A created by the apparatus of Fig. 1 and which is schematically illustrated in Fig. 5. The action of the apparatus of Fig. 4 will correspond to that described with respect to the apparatus of Fig. 1, save that when the basic frequency-modulated

wave A reaches the unit 12a, it will not in this instance be amplitude-modulated but will be merely further amplified by the said unit 12a.

There will now be described the mode of applying supplemental frequency-modulations to the basic frequency-modulated wave A, in order to cause the said wave A to shift from the pattern schematically indicated by full lines in Figs. 5 and 8 to the pattern schematically indicated by the broken line in Fig. 8.

It will be recollected from the description of the operation of the apparatus of Fig. 1, that the cathode-bias network of the tube 35a of the wave-generating unit 12a had applied thereto a varying voltage which served to vary the quench-frequency between the predetermined frequency-limits. In the unit 12a as utilized in the apparatus of Fig. 4, an additional voltage-variation is utilized by being applied to the grid-circuit of the tube 35a. This voltage-variation last referred to will be under the control of the signal-input unit 12ab and will serve to vary the rate of frequency-variation. The action of the voltage-variation in the grid-circuit of the tube 35a as just referred to, will thus serve to determine the character of the supplemental frequency-modulation which serves to convert the pattern indicated by full line in Fig. 8 into the pattern indicated by the broken line in the same figure.

It may here be noted that the cycle of supplemental modulation illustrated in Fig. 6 is here applied in its end effect as an additional frequency-modulation, whereas the same cycles of supplemental modulation as applied in the apparatus of Fig. 1, has the end result of a supplemental amplitude-modulation to thus produce the doubly-modulated wave illustrated in Fig. 7.

In producing the companion double-frequency-modulated wave B, the supplemental frequency-modulation is determined by the variation in the voltage of the grid-circuit of the tube 35b of the wave-generating unit 12b. The said voltage-variation emanates from the signal applied to the terminals of the signal-input unit 12ab.

From the foregoing it will be seen that the apparatus of Fig. 4 will transmit through its antenna 10ab, the two waves A and B which are, in this instance, both doubly-frequency-modulated.

The receiving apparatus of Fig. 2 may be utilized to extract the intelligence in a manner corresponding to the mode described in connection with the description of the extraction of the intelligence from the waves as transmitted by the apparatus of Fig. 1. In this instance, however, the tuned networks of the units 60bc, 62 and 63 will be appropriately set to receive, in a manner well known in the art, the supplemental or second frequency-modulation possessed by the wave B under the circumstances here being described.

Thus the signal component of a doubly-frequency-modulated wave B in which the signal component is applied as a supplemental or secondary frequency-modulation will be extracted by tuning the networks of the units 60bc, 62 and 63 so that the band-width of the signal frequency-modulation will be received on the side of the resonance-curve representing the band-pass characteristics of the tuned networks, rather than on the crest of the resonance-curve, which is the case when the signal component is in the form of supplemental or secondary amplitude-modulation.

The invention may be carried out in other specific ways than those herein set forth without

departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A method for electrically communicating intelligence, which method comprises: coincidentally transmitting two frequency-modulated carrier-waves each of which carrier-waves has at least one of its frequency-limits differing from the similar frequency-limit of the other of said carrier-waves; additionally modulating at least one of the said frequency-modulated carrier-waves by imposing thereon the intelligence or signal to be transmitted; and at a receiving-station extracting the intelligence from the doubly-modulated carried-wave under the control of the other of the said carrier-waves.

2. A method for electrically communicating intelligence, which method comprises: coincidentally transmitting two frequency-modulated carrier-waves each of which carrier-waves has at least one of its frequency-limits differing from the similar frequency-limit of the other of said carrier-waves; additionally modulating at least one of the said frequency-modulated carrier-waves by imposing thereon the intelligence or signal to be transmitted; and at a receiving-station extracting the intelligence from the doubly-modulated carrier-wave under the concurrent control of the other of the aforesaid transmitted frequency-modulated carrier-waves and a local frequency-modulated wave generated at the receiving-station.

3. A method for electrically communicating intelligence, which method comprises: coincidentally transmitting two frequency-modulated carrier-waves each of which carrier-waves has at least one of its frequency-limits differing from the similar frequency-limit of the other of said carrier-waves; additionally modulating at least one of the said frequency-modulated carrier-waves by imposing thereon the intelligence or signal to be transmitted; at a receiving-station extracting the intelligence from the doubly-modulated carrier-wave under the control of a local frequency-modulated wave generated at the receiving-station; and controlling the said locally-generated wave by the other of the first-mentioned transmitted carrier-waves.

4. A method for electrically communicating intelligence, which method comprises: coincidentally transmitting two frequency-modulated carrier-waves each of which carrier-waves has both its upper frequency-limit and its lower frequency-limit differing from the similar limits of the other of said carrier-waves; additionally modulating at least one of the said frequency-modulated carrier-waves by imposing thereon the intelligence or signal to be transmitted; at a receiving-station extracting the intelligence from the doubly-modulated carrier-wave under the control of a local frequency-modulated wave generated at the receiving-station; and controlling the said locally-generated wave by the other of the first-mentioned transmitted carrier-waves.

5. A method for electrically communicating intelligence, which method comprises: coincidentally transmitting two frequency-modulated carrier-waves each of which carrier-waves has at least one of its frequency-limits differing from the similar frequency-limit of the other of said

carrier-waves; additionally modulating both of the said frequency-modulated carrier-waves by imposing the intelligence or signal to be transmitted on each of the said carrier-waves but in out-of-phase relationship respectively; and at a receiving-station extracting the intelligence from one of the now doubly-modulated carrier-waves under the control of the other of said doubly-modulated carrier-waves.

6. A method for electrically communicating intelligence, which method comprises: coincidentally transmitting two frequency-modulated carrier-waves each of which carrier-waves has at least one of its frequency-limits differing from the similar frequency-limit of the other of said carrier-waves; additionally modulating both of the said frequency-modulated carrier-waves by imposing the intelligence or signal to be transmitted on each of the said carrier-waves but in out-of-phase relationship respectively; and at a receiving-station extracting the intelligence from one of the now double-modulated carrier-waves under the concurrent control of the other of said doubly-modulated carrier-waves and a local frequency-modulated wave generated at the receiving-station.

7. A method for electrically communicating intelligence, which method comprises: coincidentally transmitting two frequency-modulated carrier-waves each of which carrier-waves has at least one of its frequency-limits differing from the similar frequency-limit of the other of said carrier-waves; additionally modulating both of the said frequency-modulated carrier-waves by imposing the intelligence or signal to be transmitted on each of the said carrier-waves but in out-of-phase relationship respectively; at a receiving-station extracting the intelligence from one of the now doubly-modulated carrier-waves under the control of a local frequency-modulated wave generated at the receiving-station; and controlling the said locally-generated wave by the other of the aforesaid doubly-modulated transmitted carrier-waves.

8. A method for electrically communicating intelligence, which method comprises: coincidentally transmitting two frequency-modulated carrier-waves, each of which carrier-waves has both its upper frequency-limit and its lower frequency-limit differing from the similar limits of the other of said carrier-waves, the difference between the respective upper frequency-limits of the two said carrier-waves differing from the difference between the respective lower frequency-limits thereof; additionally modulating at least one of the said carrier-waves by imposing the intelligence or signal to be transmitted thereon; and at a receiving-station extracting the intelligence from the doubly-modulated one of the aforesaid carrier-waves under the control of the other of said carrier-waves.

9. A method for electrically communicating intelligence, which method comprises: coincidentally transmitting two frequency-modulated carrier-waves each having a curve of frequency-differentiation which is substantially-logarithmic, each of which carrier-waves has at least one of its frequency-limits differing from the similar frequency-limit of the other of said carrier-

waves; additionally modulating at least one of the said frequency-modulated carrier-waves by imposing thereon the intelligence or signal to be transmitted, and at a receiving-station extracting the intelligence from the double-modulated one of the aforesaid carrier-waves under the control of the other of the said carrier-waves.

10. A method for electrically communicating intelligence, which method comprises: coincidentally transmitting two frequency-modulated carrier-waves each having a curve of frequency-differentiation which is substantially-logarithmic and substantially-linear, each of which carrier-waves has at least one of its frequency-limits differing from the similar frequency-limit of the other of said carrier-waves; additionally modulating at least one of the frequency-modulated carrier-waves by imposing thereon the intelligence or signal to be transmitted; and at a receiving-station extracting the intelligence from the double-modulated one of the aforesaid carrier-waves under the control of the other of the said carrier-waves.

11. A method for electrically communicating intelligence, which method comprises: coincidentally transmitting two frequency-modulated carrier-waves each having a curve of frequency-differentiation which is substantially-logarithmic, each of which carrier-waves has at least one of its frequency-limits differing from the similar frequency-limit of the other of said carrier-waves; additionally modulating both of the said frequency-modulated carrier-waves by imposing thereon the intelligence or signal to be transmitted; and at a receiving-station extracting the intelligence from one of the now doubly-modulated carrier-waves under the control of the other of the said doubly-modulated carrier-waves.

12. A method for electrically communicating intelligence, which method comprises: coincidentally transmitting two frequency-modulated carrier-waves each having a curve of frequency-differentiation which is substantially-logarithmic and substantially-linear, each of which carrier-waves has at least one of its frequency-limits differing from the similar frequency-limit of the other of said carrier-waves; additionally modulating both of the said frequency-modulated carrier-waves by imposing thereon the intelligence or signal to be transmitted; and at a receiving-station extracting the intelligence from one of the now doubly-modulated carrier-waves under the control of the other of the said doubly-modulated carrier-waves.
